UNITED STATES PATENT OFFICE.

ERNEST FLAGG, OF NEW YORK, N. Y.

BUILDING CONSTRUCTION.

Application filed June 17, 1926. Serial No. 116,673.

The present invention is concerned with improvements in building constructions, particularly with the provision of a building construction which will permit the rapid 5 erection of buildings by unskilled labor with great rapidity and at little cost.

An object of the invention is to provide a building construction of this character which will not only eliminate the slow 10 methods commonly used in stone setting and the skilled labor ordinarily required, but which will result in a construction more nearly perfect and more substantial than that which can be obtained by the usual 15 means.

A building constructed in accordance with a preferred embodiment of the present invention consists of a series of piers formed 20 of superimposed concrete blocks with cur- tain walls of brick connecting the piers and lying flush with their outer faces. The blocks which form the piers are provided with aligned openings therein and concrete is 25 poured into the openings to connect all of the blocks together after the blocks have been piled one upon the other. Preferably the bed faces of the blocks are concave or 30 dished, so that the concrete may flow between the bed faces and securely lock all of 35 the blocks in the pier together.

Preferably also, the blocks of each pier are alternately long and short, so that certain blocks of adjacent piers will project inwardly and afford a convenient support for 40 the beams or lintels upon which the ends of the cross beams are supported.

In cases where an unusually strong construction is desired, reinforcing rods may be 45 inserted in the aligned openings in the blocks, and the concrete may be tamped to force it firmly into the pockets defined by the mating concave bed faces of the blocks.

With the above noted and other objects in view, the invention consists in certain 50 novel features of construction and combinations and arrangements of parts, as will be more fully hereinafter set forth and pointed out in the claims. The invention may be more fully understood from the following 55 description in connection with the accompanying drawings, wherein—

Fig. 1 is a fragmentary view in side elevation of a building constructed in accordance with the present invention.

Fig. 2 is a view in transverse section on the line 2—2 of Fig. 1.

Fig. 3 is a vertical sectional view through one of the piers on approximately the line 3—3 of Fig. 1.

Figs. 4 and 5 are perspective views of two 60 of the blocks used in forming the piers.

Figure 6 is a detail sectional view on line 6—6 of Figure 2, looking in the direction of the arrow.

In producing a building in accordance 65 with the present invention, I use a series of superimposed molded blocks such for instance as the block 10 shown in Fig. 4. These blocks are formed with pockets or 70 are suitably dished at 11 on their bed faces, so that when two of the blocks are superimposed, only the edges of the blocks will 75 contact with each other. The two bed faces of the block are connected by a relatively capacious opening 12 extending through the block.

The rectangular blocks of Fig. 4 are 80 preferably used for the corner piers of the building, and as shown are piled one upon the other to produce a pier. In forming 85 the corner piers, the longer side of one block preferably extends parallel with the shorter side of the superadjacent and subjacent blocks, so that when viewed from the side, alternate blocks of the pier will project beyond the others.

After the blocks have been assembled to 90 form the pier, concrete is poured into the cylindrical bore defined by the aligned openings 12 of all of the blocks, and will flow into the pockets defined by the cooperating concavities 11 in the bed faces of adjacent 95 blocks. Where an unusually strong construction is required, a reinforcing rod such as the metal pipe 13 may be inserted in the aligned openings 12 before the concrete is poured. The concrete may be tamped down to force it into the pockets between the blocks and to assure firm interlocking of the 100 blocks of the pier.

The piers which are used adjacent window or door frames are formed in substantially the same manner, but the blocks 14 may be of the special shape shown in Fig. 5, including tongues 15 which interlock with and back the sash or door frames 16, shown in Fig. 2.

The blocks 14 are of alternately different 110 lengths, so that the piers adjacent the sash frame will also present blocks of alternating length as shown in Fig. 1. Openings 12^a and concavities 11^a in the blocks 14 corre-

sponding with the openings 12 and the concavities 11 in the blocks 10, and reinforcing rods such as 13^a may be used if desired.

The piers are erected by placing the lowest block in a level position and piling all of the upper blocks plumb with the lower blocks. Thus, unskilled labor may be used in the building of the piers. The interspaces between the piers are filled in by sections of brick wall indicated at 16^a. This wall may be of the ordinary curtain wall type, of a thickness corresponding to the width of a single brick. Preferably the rear faces of the brick walls are plastered as at 17 to close any chinks which may be present between the bricks.

The inside wall of the building may be finished in any suitable manner, such for instance as by the use of metal lathing indicated in dotted lines at 18.

The inwardly projecting ends of the blocks of adjacent piers offer a convenient support for the ends of a beam or lintel indicated in dotted lines at 19, and cross beams may be mounted upon the beams or lintels thus supported. These beams or lintels, it is to be understood, will be disposed in the air space between the brick curtain wall and the inner wall 18.

Obviously, various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. A building construction including a series of spaced piers each formed of superimposed molded blocks, the blocks having aligned openings therein for receiving concrete poured in from the top after the blocks have been piled, and curtain walls connecting the piers and flush with the outer faces thereof.

2. A building construction including a se-

ries of spaced piers each formed of superimposed molded blocks, the blocks having aligned openings therein for receiving concrete poured in from the top after the blocks have been piled, and curtain walls connecting the piers, alternate blocks of the piers extending further into the curtain walls than the others and being adapted to constitute supports for beams or lintels.

3. A building construction including a series of spaced piers each formed of superimposed molded blocks, the blocks having aligned openings therein for receiving concrete poured in from the top after the blocks have been piled, and curtain walls connecting the piers, the bed faces of the blocks having concavities therein, whereby the blocks contact only at their edges and the concrete positively locks all of the blocks against displacement.

4. A building construction including a series of spaced piers each formed of superimposed molded blocks, the blocks having aligned openings therein for receiving concrete poured in from the top after the blocks have been piled, and curtain walls connecting the piers, inner walls secured to the inner faces of the piers and defining with said outer walls an air space, the outer wall being of a single thickness of brick and plastered on its inner face to close the chinks between the bricks.

5. As a new article of manufacture, a solid molded building block having concavities in its two bed faces and having an opening extending therethrough and connecting the two concavities.

6. A method of building construction which includes the step of piling one upon the other to form a pier, a series of molded blocks having aligned openings therein and having concavities in their bed faces, then pouring concrete into the vertical passageway defined by the aligned openings, whereby the concrete will run laterally into the concavities and lock the blocks together.

ERNEST FLAGG.
